UNITED STATES PATENT OFFICE.

GEORGE S. SWITZER, OF GRAND RAPIDS, MICHIGAN.

AIR-BRAKE VALVE.

1,127,826.

Specification of Letters Patent.

Patented Feb. 9, 1915.

Application filed November 10, 1913. Serial No. 800,211.

To all whom it may concern:

Be it known that I, GEORGE S. SWITZER, a citizen of the United States, residing at Grand Rapids, in the county of Kent and 5 State of Michigan, have invented certain new and useful Improvements in Air-Brake Valves, of which the following is a specification.

My invention relates to improvements in 10 brake valves for use with air brakes on railroad trains, and its objects are: First, to provide an auxiliary valve to use in conjunction with ordinary Westinghouse valves in emergencies, as if the Westinghouse valve 15 became inoperative. Second, to provide an auxiliary valve of simple construction that could be easily adjusted to meet all of the demands that might be required of the Westinghouse valve; and, third, to provide 20 an auxiliary valve that will remain absolutely inactive when the Westinghouse valve is in operative condition, and may be immediately switched into operative position if the Westinghouse valve becomes defective. 25 I attain these objects by the mechanism illustrated in the accompanying drawing, in which—

Figure 1 is an elevation of an ordinary Westinghouse system of valves, pipes, and 30 air compression appliances, with my appliance shown in connection therewith. Fig. 2 is a plan of the same. Fig. 3 is a sectional plan of a coupling by means of which the two valves may be connected with one line 35 of brake pipes and either valve used as may be desired. Fig. 4 is a vertical section of my valve looking to the left from the line X X of Fig. 6. Fig. 5 is a like view looking to the right from said line. 40 Fig. 6 is a sectional view of my valve practically on the line y y of Fig. 4 with the parts in position for service application. Fig. 7 is the same with the parts in position to hold the pressure that has passed into 45 the brake cylinder when the parts were in service application position. Fig. 8 is the same showing the parts in position for emergency application, and Fig. 9 is the same with the parts shown in position to be 50 charged from the main reservoir.

Similar reference characters refer to similar parts throughout the several views.

My valve consists of a cylinder 1 which is provided with an inlet opening 2 and two 55 outlet openings, 11 and 18, and with a vertical port 6 that leads to the opening 18, and

a port 10 that leads to the open air. This cylinder has a cap B that is secured to one end thereof and has an inlet opening 19 to the center of the cylinder. The opening in 60 the cylinder is made slightly tapering and a plug or barrel A is fitted therein to be made to oscillate freely, and yet to form an air tight joint or bearing in the cylinder. This barrel has a central chamber 13 in 65 position to receive air from the opening 19, and also a port 12 that leads from the chamber 13 in position to be readily made to register with the port or opening 11 in the cylinder, by turning the barrel A to the 70 proper position in the cylinder. This barrel is also provided with a port 3 that extends about one third of the way around the upper end of the barrel, and a port 15 that extends from the side of the port 3 75 across the top of the barrel to the opposite side thereof, the two ports being so located that when the port 3 registers with the opening 2 the port 15 may be made to register with the opening 11 in the cylinder. The 80 barrel A also has a port 8—9 designed to form an opening between the ports 10 and 11 in the cylinder 1. This valve is properly connected in the line 27—37 of the air brake system, and the barrel A is manipulated by means of the lever 17, all as hereinafter more fully explained.

In the construction of my valve I make use of a cylinder 1 having a valve barrel A and a retaining plate B. The cylinder 1 90 has an opening 2 for the reception of the pipe 27 which is connected, through the pipe 25, with the compression chamber 22 so that compressed air may be conducted directly from said chamber 22 into the port 3. 95 When the valve lever 17 is placed in the position of the dotted lines in Fig. 6 the cross port 15 is made to open directly into the valve port 11 as indicated by the dotted lines in said figure and allow a free flow of 100 compressed air from the chamber 22 through the port 11 and the pipe 25, and the pipe 31 to the Y valve 33 and into the pipe 35 which passes directly to the triple valves common in air brake construction 105 and not necessary to be described in this connection as it has no direct connection with my valve. When the valve barrel A is in this position the port 7, indicated by dotted lines in the several views, will be carried around so that its left hand wall will be at the point indicated by the point of 110

the arrow in Fig. 6 and an opening will be formed from the brake cylinders 24 and 38, through the ports 6, 7 and 4 to the open air.

When the lever 17 is carried to the position indicated in Fig. 7 the valve barrel A is carried around to such a position that all ports in the valve are closed and no air pressure can pass through the valve 1, hence any pressure in any pipe leading to or from this valve will be held constant in said pipe. If it is desired to reduce the pressure in the train brake pipe 31 only the lever 17 is carried over to the position indicated by the solid lines in Fig. 6 when the port 9 is opened to the port 10 and the air in the train brake pipe is allowed to escape through these ports. It will be noted, by reference to Fig. 5, that the ports 5 and 7 are on different planes so that when the lever 17 is in the position shown in Fig. 6 there is no communication between the ports 4 and 5 for the escape of air from the compression chamber 13 in the barrel A to the open air, and the port 5 is always blanked except when the valve barrel is carried over to emergency position, indicated in Fig. 8, when a full, free flow of air is allowed from the train brake pipes 31-35 through the ports 11, 8 and 10 to cause the immediate setting of the train brakes; and the port 5 through the wall of the valve barrel A will be carried around to connect directly with the port 6 and the opening 18 through which direct action is had upon the engine and tender brakes through the pipe 37 and the brake cylinders 24-38, and all brakes, both on the train and on the engine and tender, are immediately set.

With the lever 17 in the position indicated in Fig. 9 all valves and ports are closed except that the port 12 is opened to the port 11 and pressure is taken directly from the compression chamber 22, around the reducing valve 28 and into the chamber 13 in the valve barrel A and thence to the train brake pipes under the full pressure of the chamber 22. When this position of the valve barrel is reached notice thereof is given by the escape of air through the small orifice 14 to the open air. This valve is used as an auxiliary to the E. T. Westinghouse automatic brake valve indicated at 21 to which compressed air is conducted from the chamber 22 through the pipe 25, my valve 55 being supplied from this pipe by switching through the pipe 27 to the direct acting ports 2, 3, 15 and 11, and for main pressure service the air is again switched through the pipe 30 into the port 19, the compression chamber 13 and the port 12 into the brake valve pipe, as hereinbefore described. When the E. T. valve is in use there is always a back pressure from the brake pipes 35 to the valve 1 by way of the port 5 in the Y valve 33, but if it is desired to cut out

the E. T. valve this can be done by means of the plug valve 34 in the port a of the valve 33, or by the valve 40 which is located in the pipe 39 that connects the valve 21 with the pipe 41, and by manipulating the actuating lever C of the E. T. valve in the usual way, and the valve 1 may be made effective by opening the valves 29 and 44 and 45 and manipulating the lever 17 as hereinbefore described.

The parts 32 and 36 represent the ordinary flexible connecting pipes in use with all air brakes or connecting the pipes between cars.

26 represents a cut-off valve in the pipe 25 with which to cut off the flow of air from the chamber 22 to the several brake pipes in a train service. The pipe 42 is designed to form a connection between the brake cylinder 24 and the pipe 37 and, incidentally, with the brake cylinder 23, so that when pressure is allowed to pass out of the chamber 13 into the pipe 37 the entire system, including the chambers 23 and 24 and the chamber 38 will be filled with air of equal pressure.

At 28 I have shown the ordinary reducing valve in common use for reducing the pressure from the chamber 22 before it enters the valve 1, or other operating valve, so that the pressure in the chamber 13 is always higher than that in the upper portions of the valve or the ports 3-15.

16 represents an arm and bracket by means of which the valve may be bolted to a supporting element, and 20 represents a guard for holding the lever 17 in desired positions.

The auxiliary valve 1 should be placed in the engine cab and in the line of brake pipes in such a position as to be easily accessible to the engineer without changing his position or varying his movements from those necessary to properly and conveniently manipulate the ordinary engineer's valve, whenever the necessity arises for bringing this valve into use.

When using my valve simply as an auxiliary to the common E. T. automatic valve, and the latter is working correctly, I generally close the valve 29 and cut out the flow of air from the chamber 22 to this valve, but leave the valves 44 and 45 open and the lever 17 in operative position, or the position indicated by the dotted lines in Fig. 6, but if the E. T. valve does not work properly the valves 34 and 40 should be closed and the valves 29, 44 and 45 opened so that a free flow of air may be insured from the chamber 22 to, and through the valve 1, as hereinbefore described in connection with the several positions of the lever 17 and the several ports in this valve.

While I have so far described my valve simply as an auxiliary to the E. T. valve

and for use only in cases of extreme emergencies, it will be readily understood that it may be used with perfect success independent, and in the place of any other form 5 of brake valve, and, further, that with the peculiar construction and distribution of the valve barrel and its several ports this valve may be used independent of any cut-off valves before, or back of it and all manipulations of the valve controlled and regulated 10 by the lever 17.

43 is the pipe that connects the valve 1, from the opening 18, with the pipe 37 that charges the engine and tender brake cylinders 23, 24 and 38.

It is to be understood that the valve pipes 31, 35 are always open from the triple valves back to the valve 45, and when this valve is open they are always open to my valve so 20 that even though the angle valve or plug 34 be closed accidentally or maliciously it is impossible to cut my valve off from the train 25 brake system, and the operativeness of the brake system will not be affected even though the ordinary or E. T. valve 21 be entirely cut off from the system back of the tender where the angle valve or Y connection 33 is located.

I wish it to be distinctly understood that 30 the angle valve or Y connection 33 is one of the most necessary elements in my invention as without it the use of my valve in the same line with, but independent of the E. T. valve would be impossible, and the inaccessible 35 position in which the Y valve is located, at the back end of the engine tender renders it very desirable that the brake connections be in position to be worked by my valve even though the E. T. valve 21 is cut out, as, for 40 instance, in case of a hold up, where the parties attempting to hold up the train have closed the valve 34 to the E. T. valve the engineer still has direct access to his train 45 brakes from my valve, while, at the same time, my valve is so arranged that even though in condition to be immediately connected with the train brakes it will, when all ports are closed, cut off all flow of air back from the brakes.

50 The port 6 is so located that it opens a direct passage way from the port 3 to the opening 18 when the barrel is in the position indicated in Figs. 4, 5, 6 and 8, to close said passage way when the barrel is in the position 55 indicated in Fig. 7, and to open into the port 8 when the barrel is in the position indicated in Fig. 9. Thus, when the compressed air is being taken from the compression chamber 22 directly into the chamber 13 60 and thence directly to the train brakes through the opening 11, all openings from the compressed air chambers or pipes to the opening 18 are cut off so there is no possibility of compressed air being forced into 65 or being allowed to escape from the engine

and brake cylinders 23 and 24 to in any way affect the action of these brakes.

What I claim as new, and desire to secure by Letters Patent of the United States, is:—

1. In combination with the compression chamber, air pipes and brake mechanism of a railway air brake system, a valve consisting of an outer cylinder having an inflow pipe and an outflow pipe directly opposite each other, and having an open port through its wall, a valve barrel having a peripheral port in one side and a branch therefrom directly across the barrel in position to be made to form a passage from the inflow pipe to the outflow pipe to actuate the brakes, and, also, having a port for conducting air from the outflow pipe through the valve and to the open air to set the brakes, and means for operating the valve for setting or releasing the brakes.

2. In combination with the compression chamber, conductor pipes and brake mechanism of an air brake system for railway trains, a valve consisting of a cylinder, an inflow pipe and an outflow pipe connected with said cylinder on opposite sides thereof, said cylinder having a port through the wall near the outflow pipe, an outflow pipe at right angles with the first named pipes but on a different plane, the cylinder having a longitudinal port leading from the plane of the inflow and outflow pipes to the right angle outflow pipe, said cylinder having a port through its wall near the right angle outflow pipe, a valve barrel having a peripheral port in one side that may be made to cover the inflow pipe and the width of the longitudinal port in the cylinder, also a cross port that may be made to conduct air from the inflow pipe to the outflow pipe on the same plane, a second peripheral port to connect the first mentioned outflow pipe with the open air port in the cylinder wall, and a peripheral port on the plane of the right angle outflow pipe in position to connect this outflow pipe with the port through the wall of the cylinder when the barrel is in proper position, and means for operating the valve to apply and release the brake mechanism, as described.

3. In combination with the compression chamber, conductor pipes and brake mechanism of an air brake system for railway trains, an outer cylinder, an inflow pipe and an outflow pipe near one end of the cylinder, an outflow pipe near the other end of the cylinder, the cylinder having a longitudinal port extending from the plane of the inflow and outflow pipes to the plane of the single outflow pipe, and two ports through its wall to the open air, a valve barrel having peripheral and cross ports in position to form a free passage from the inflow pipe to the outflow pipe and also

from the inflow pipe to the longitudinal port, and also ports for conducting air from the outflow pipes to the open air when the barrel is properly positioned, said barrel also having a chamber in one end and a port leading therefrom to the plane of the inflow and outflow pipes and also a port through its wall on the plane of the single outflow pipe, a cap for closing the end of the cylinder, an auxiliary inflow pipe leading through said cap to the chamber in the barrel, and means for revolving the valve barrel to bring the several ports in desired positions to set and release the brakes, substantially as shown and described.

4. In combination with the compression chamber, conductor pipes, and brake mechanism of an air brake system for railway cars, a valve consisting of an outer cylinder, an inflow pipe and an outflow pipe connected near one end of the cylinder and an outflow pipe connected near the other end of the cylinder, said cylinder having a longitudinal port connecting the plane of one outflow pipe with the other outflow pipe and two ports through its wall to the open air, a valve barrel having peripheral and cross ports and a chamber in one end, also having a port leading from said chamber to the plane of the inflow pipe, and also having a port leading from the chamber to the plane of the outflow pipe at the other end of the cylinder, a cap for closing the end of the cylinder and the chamber in the barrel, a reducing valve in the main inflow pipe near the cylinder, an auxiliary inflow pipe passing from the main inflow pipe to the cap and opening into the chamber in the barrel, and means for revolving the barrel to adjust the several ports to desired positions.

5. In combination with the compression chamber, air conducting pipes and brake mechanism in an air brake system for railway cars, an outer cylinder having necessary ports for governing the system, an inflow pipe and an outflow pipe near one end of the cylinder for operating the train brakes, an outflow pipe near the other end of the cylinder for operating the brakes on the engine and tender, a valve barrel having a central chamber in one end, an auxiliary inflow pipe leading to said chamber, said chamber and barrel having ports arranged to coat for actuating the train brakes and the engine brakes simultaneously or separately as desired, and means for actuating the valve barrel to properly adjust said ports for setting or releasing said several brakes as desired.

6. In combination with the compression chamber, air conductor pipes and brake mechanism in an air brake system for railway cars, a valve consisting of an outer cylinder, having necessary ports therein for re-

ceiving and discharging compressed air as necessary, an inflow pipe and an outflow pipe near one end of the cylinder for operating the train brakes, an outflow pipe near the other end of the cylinder for operating the engine brakes, a valve barrel having a compression chamber and ports for acting with the several ports and air pipes, an auxiliary inflow pipe to said chamber, and means for actuating the barrel to carry its ports in proper connection with the ports in the cylinder to produce the desired results whereby the several sets of ports may be made to act simultaneously or separately, as desired.

7. In an auxiliary air brake valve, an outer cylinder an inflow pipe and an outflow pipe directly opposite each other and on the same plane, and also having an open air port near, and on the same plane with the outflow pipe, a barrel in the cylinder having a peripheral, and a diametrical port on the same plane with the inflow pipe, and arranged to form an open port from the inflow pipe to the outflow pipe, and having a second peripheral port arranged to connect the outflow pipe with the open air port, and a lever for actuating the barrel.

8. In an auxiliary air brake valve, an outer cylinder having an inflow pipe and an outflow pipe, and also having an open port to the outside atmosphere, all on the same plane, also having an outflow pipe at right angles with the inflow pipe but near the opposite end of the cylinder, the cylinder provided with a vertical port extending from the plane of the inflow pipe to the second named outflow pipe, a barrel fitted into the cylinder and having a peripheral port and a diametrical port arranged to form an open passage between the inflow pipe and the outflow pipe, also having a peripheral port arranged to form a passageway from the first mentioned outflow pipe to the open air port, and means for securing the barrel in the cylinder, and means for actuating the barrel to arrange the ports as desired.

9. In an auxiliary air brake valve, a cylinder having an inflow pipe and an outflow pipe directly opposite each other and a port through its wall, an outflow pipe near the opposite end of the cylinder, the cylinder having a longitudinal port from the plane of the inflow pipe to the second mentioned outflow pipe, a barrel closely fitted into the cylinder and having a peripheral port and a diametrical port connected and arranged to form an air passageway from the inflow pipe to the outflow pipe at one end of the cylinder, and having a second peripheral port arranged to form a passageway from this outflow port to the open air port, the barrel having a central chamber and a port arranged to form a passageway from the center of the barrel to the first mentioned

outflow pipe, a cap arranged to secure the barrel into the cylinder, an inflow pipe leading through the cap into the central chamber in the barrel, and a lever for actuating the barrel to properly arrange the several ports for operating the brake mechanism as desired.
